(57) CLAIM

The ornamental design for a cleaning device for an electric shaver, as shown and described.

DESCRIPTION

FIG. 1 is a perspective front elevational view of cleaning device for an electric shaver from above, showing our design;

FIG. 2 is a left side view of the appliance;

FIG. 3 is a front view thereof;

FIG. 4 is a right side view thereof;

FIG. 5 is a rear view thereof;

FIG. 6 is a top plan view thereof; and,

FIG. 7 is a bottom plan view thereof.
